FUSED MULTIPLE ELECTRICAL OUTLET BOX WITH MASTER SWITCH AND PILOT LIGHT

Robert D. Kahn, Hewlett Harbor, N.Y., assignor to
Fectro, Inc., Rockville Centre, N.Y.

Filed May 11, 1964, Ser. No. 79,931

Term of patent 14 years

(Cl. D26—1)

FIG. 1

FIG. 2

FIG. 3

FIG. 4

FIG. 5

FIG. 1 is a top plan view of a fused multiple electrical outlet box with master switch and pilot light, showing my new design;

FIG. 2 is a front elevational view, the rear being substantially a mirror image thereof;

FIG. 3 is a bottom plan view;

FIG. 4 is a left side elevational view; and

FIG. 5 is a right side elevational view thereof.

I claim:

The ornamental design for a fused multiple electrical outlet box with master switch and pilot light, substantially as shown and described.
